TOY

Julien F. Winnemore, Washington, D. C.

Application June 29, 1935, Serial No. 29,163

9 Claims. (Cl. 46—201)

The present invention relates to toys.

More specifically, the invention relates to improvements in structural toys of the vehicle type and comprises a plurality of interchangeable parts for the construction of various types of toy cars.

A primary object of the present invention is the provision of a toy comprising a set of toy car constructing elements which are of simple form and which are adapted for the construction of various types of toy cars and which are further adapted for association with each other in such manner that any one type of car can readily be changed to another type of car by interchanging some or all of the elements.

A further object of the invention is the provision of a base member and a plurality of blocks of specific structural formation and of such proportions relative to the base member and to each other that various toy automobiles of the streamline type can be readily constructed upon judicious arrangements of the blocks upon the base member.

A further object of the invention is the provision of a toy car base member which is provided with means for removably receiving rolling means and which is further provided with arcuate ends with coupling receiving means adjacent the ends for the reception of yieldable coupling means for maintaining the arcuate ends in contact and permitting rolling engagement therebetween.

A still further object of the invention is the provision of a toy comprising toy car constructing elements which can be manufactured and sold at relatively low cost.

Reference will be had to the accompanying drawings illustrating a preferred embodiment of the invention and wherein similar reference characters indicate similar parts.

40 In the drawings:

Figure 1 is a side elevational view of a toy car constructed from a plurality of elements later to be described and which indicates one of many possible arrangements of standard blocks forming the subject-matter of the present application.

Fig. 2 is a front elevation of the construction illustrated in Fig. 1.

Fig. 3 is a side elevational view of a sectional double-lengthened car showing a further arrangement of the construction elements of the invention.

Fig. 4 is a side elevational view of a member from which several blocks are constructed as will be later described.

Figs. 5 and 6 illustrate in side and end view respectively the blocks formed from the member illustrated in Fig. 4.

Fig. 7 is a perspective view of one of a plurality of primary blocks.

Figs. 8, 9, and 10 are perspective views of secondary blocks.

Fig. 11 is a bottom plan view of the base member showing a ball retaining means associated therewith.

Fig. 12 is a sectional view as seen on line 12—12 of Fig. 11.

Fig. 13 is a view similar to Fig. 1 illustrating a further arrangement of blocks for providing a different form of toy car.

Fig. 14 is a front elevation of the construction illustrated in Fig. 13.

Fig. 15 is a bottom plan view of the construction illustrated in Fig. 13.

Fig. 16 is a plan view of a preferred form of a draw member.

Fig. 17 is a top plan view of a train of cars disclosing a modified form of draw member.

Fig. 18 is a side elevation of the construction illustrated in Fig. 17.

Fig. 19 is a perspective view of one of the blocks showing a recess in each of the faces with a pin mounted in one of the holes.

Fig. 20 is a perspective view of one of the pins.

Referring to the drawings by reference characters, 10 designates a base member which as indicated is preferably of generally rectangular form in plan with rounded ends and is of sufficient thickness to accommodate ball rollers later to be described. The base member 10 in its preferred form is provided with a diagonally disposed slot 11 adjacent each end thereof and which extends throughout the width of the base member 10 for a purpose later to be described. The base member 10 is further provided with a plurality of circular recesses 12 in the bottom thereof for receiving corresponding balls 13 whereby the base member is supported for universal planular movement thus well adapting it for use in toy cars. It is to be particularly noted that the recesses 12 are of greater depth than the radius of the balls 13 whereby the likelihood of the balls becoming dislodged from the recesses is substantially reduced.

The invention comprises aside from the base member 10 and balls 13 a plurality of construction blocks which are of such form that they are well adapted for interchangeable arrangement on the base member 10 for providing various types of toy car bodies. The blocks are illustrated in Figs. 5

to 10 inclusive and comprise a set of primary blocks 14 which as indicated in Fig. 7 are preferably of cubical form and are adapted for the construction of the main portion of the toy car body as will be later pointed out. The blocks also comprise a plurality of secondary blocks 15, 16, and 17, as is illustrated in Figs. 8, 9, and 10 respectively, and which are adapted for interchangeable association with the main blocks 14 in the construction of various forms of toy cars. The blocks further comprise a plurality of block members 18 which may be used to simulate fenders, turrets, etc., and which are preferably constructed from an egg-shaped member E, illustrated in Fig. 4, by dividing said member into four parts in planes in the major axis of the member and intersecting each other at right angles, as will be clear from Figs. 5 and 6. The blocks 18, by being constructed in the manner disclosed, are each provided with a pair of right angularly disposed seating faces 19 which are subtended by an arcuate surface 21.

It will be seen from the foregoing that the invention comprises a relatively small number of construction elements, it being understood, however, that a plurality of each of the elements, particularly the blocks 14, are necessary for the construction of various forms of toy cars; the elements are not only relatively few in number but are of simple construction and are of standard form and, as will be later set forth, the relative dimensions of the base member and blocks are such as to present a well balanced appearance of toy car in any of the many forms which are capable of construction from the elements described. In Fig. 1 is illustrated a toy car which is constructed from twelve of the blocks 14, two each of the blocks 15 and 16, four of the blocks 17 and two of the blocks 18. The blocks 17 each have a rounded surface at one end thereof as indicated at 22 which well adapts these blocks for use in the front end of the car and the blocks 15 and 16 each have a beveled face as indicated at 23 and 24 respectively and which faces upon superposition of the blocks aline as indicated in Fig. 1, thereby well adapting these blocks for use in the rear end of the car. The car shown in Fig. 1 is given an added appearance by placing two of the blocks 18 on the top adjacent the front end with two of their faces 19 in contact and the other faces 19 in contact with blocks 14 and 17. The car shown in Fig. 1 is one of many possible forms which may be constructed from the blocks and which may readily be altered by shortening the body by using only eight blocks 14 instead of twelve and furthermore the body may be constructed from a single row of blocks in the manner indicated in Fig. 14, in which instance the blocks 18 would be placed on base member 10 and by the provision of the double faces 19 any one block 18 can be placed at either side of the car for exposing the surface 21. It is to be particularly noted in Fig. 2 that the base member 10 is slightly wider than the double row of blocks 18 whereby the base member may be readily grasped at opposite edges without danger of shifting the blocks.

In Fig. 3 is illustrated another of the possible arrangements of the elements for forming a long car, and which comprises a pair of base members 10 which are detachably connected together by a member 25 engaged within the slots 11 at adjacent ends of the bases and which member may be of any suitable construction, such for example as an elastic band which will maintain the

ends of the base members in contact as well as permit them to roll on each other at their contacting rounded ends. Disposed on the base members 10 are a plurality of blocks 14 which as indicated form the major length of the car, the body being interrupted adjacent the coupled ends to permit relative movement of the base members without displacing the blocks. The rear end of the car is formed as in Fig. 1 by the blocks 15 and 16, and the front end of the car is formed by a pair of blocks 17. The front end, of course, could be constructed as in Fig. 1 by the use of four blocks 17.

While I have disclosed a long car construction in Fig. 3 it may readily be converted into a train of cars by substituting blocks 15 and 16 for the eight rear blocks 14 on the front base member 10 and by substituting two or four blocks 17 for four or eight blocks 14 at the front end of the rear base member 10.

In Fig. 13 is illustrated still another arrangement of the blocks for providing a further form of toy car, and which comprises two blocks 14 disposed centrally of the base 10, a block 16 at the rear of the base 10, a block 17 at the front of the base 10, a block 15 disposed on block 16 as in Fig. 1 and a second block 17 disposed on blocks 14. The car is completed by disposing four of the blocks 18 on the base member 10 adjacent the corners thereof for simulating fenders. It will be seen that this arrangement of blocks provides a toy automobile closely resembling a real automobile of the streamline type.

In Figs. 17 and 18 is illustrated a still further arrangement of the elements for providing toy cars simulating a sedan being towed by a truck. As here indicated the sedan being towed is of the construction illustrated in Fig. 13 and the truck is formed by a block 17 adjacent the front of its base member 10 for simulating a radiator, a block 14 is disposed rearwardly of block 17 for simulating a seat, and four of the blocks 18 are disposed as in Fig. 13 for simulating fenders.

It is to be noted that the combined width of a pair of blocks 18 and one of any of the other blocks is substantially equal to the width of the base member 10. It is further noted that the blocks 14, 15, 16, and 17 are all of the same height and width although they are of different lengths. It will be understood, however, that the width and height of the blocks may be varied so long as they are maintained equal. This provides for the construction of bodies of uniform width and admits of the superposition of the various blocks in constructing bodies to provide alined top members. It will be further noted that blocks 17 at the bases thereof are of a length equal to the length of two of the blocks 14 as indicated in Figs. 3, 13, and 18 for providing the top portion of the body of neat appearance.

While I have illustrated several forms of toy cars and trains readily constructed from the elements, nevertheless, it is to be understood that many types of cars can be constructed, and that while I have illustrated only two of the base members 10 as being connected by the member 25 three or more may be connected in like manner to provide a train of cars of like or different forms as may be desired, in fact the base members and blocks are of such construction and of such relative proportions that an unlimited number of toy cars are capable of construction therefrom.

The blocks are preferably of different colors for providing different colored bodies. The primary blocks 14 preferably each have three different

colors, with opposite faces of the same color in order that the opposite sides of the toy car body will be of the same color when a single row of blocks is used, as in Figs. 13 and 18. Thus, as indicated in Fig. 7, the block 14 is provided with red and blue vertical faces and a top white face, the opposite faces being of corresponding color. By providing the blocks 14 with three different colors a wide selection of colors in the body is possible. The blocks 15, 16, 17, and 18 also may be of different colors for further varying the color effect of the different bodies capable of construction from the blocks disclosed.

In Fig. 1, for example, the lower rows of blocks are indicated as being blue while the upper rows may be white or any other desired color.

In Fig. 3 the lower blocks on the front base member are indicated as being red while the lower blocks on the rear base member are indicated as being blue, the upper rows of blocks may, of course, be of any desired color or colors. Various color combinations are possible with blocks of different colors, as described.

While the arrangement of the balls 13 in the recesses 12 will in most instances preclude the dislodging of the balls from the recesses, such dislodgment may happen particularly at the coupled ends of base members and accordingly my invention comprises a means for positively preventing the dislodging of the balls from their recesses while at the same time readily admitting the withdrawal from or the positioning of the balls within the recesses. The said means in a preferred form comprises a thin sheet metal member 26 illustrated in Figs. 11 and 12 and which is pivotally connected at 27 to the bottom of the base member 10, the member 26 being provided at each end thereof with a pair of apertures 28 of slightly less diameter than the balls 13 but of sufficient diameter to permit free rolling of the balls. The member 26 is provided with a tongue 29 at each end thereof which as indicated in Fig. 12 is slightly spaced from the base member 10 to provide a finger hold for springing the member 45 away from the base to clear the balls, the member 26 being swung on its pivot 27 after the ends thereof have been sprung sufficiently to clear the balls. While I have disclosed but a single member 26 for holding all four balls 13 a similar member individual to each ball may be provided if desired.

Any suitable means may be provided for pulling the car or train of cars and which preferably comprises a member 30 which, as indicated in Fig. 55 16, is preferably constructed of wire and which comprises a large loop having a straight portion 31 for engagement within one of the slots 11 in the manner illustrated in Figs. 1 and 13, the member 30 is further provided with a suitable handle 60 32. It will be seen that the slots 11 are so disposed as to interchangeably admit the connectors 25 for connecting base members in forming trains of cars or the draw member 30 for pulling a single car or a train of cars.

65 The draw member 30 while preferably of the form described may comprise arms 33 whose free ends are turned at right angles as indicated at 34 for removable engagement in apertures 35 at opposite sides of the base at one end thereof. When utilizing a draw member of this character the bases 10 would, of course, be constructed with a slot 11 at one end thereof whereby the connecting member 25 may be utilized for coupling the base members as in Figs. 3 and 18.

75 From the foregoing disclosure it will be seen

that I have provided relatively simple elements of standard form which are capable of manufacture at relatively low cost and from which toy cars or trains of cars of many different forms may readily be constructed. Furthermore, by providing a base member and body construction blocks for support on the base member without connection therewith, any of the blocks can readily be shifted or interchanged whereby any one body can readily be reconstructed to provide a body of different form.

It will be further noted that the blocks as indicated in Figs. 5 to 10 inclusive, are each of a specific structural form whereby bodies of various toy automobiles of the stream-line type can be readily constructed therefrom, the stream-line effect resulting from the angular and curvilinear shapes of the blocks as is apparent from Fig. 13, wherein the inclined faces of blocks 15 and 16, together with the curvilinear faces of blocks 15 and 17 and the arcuate blocks 18, give the body the appearance of a real automobile of the stream-line type, and this effect is more or less pronounced in the other possible body formations illustrated.

While in the preferred form of the invention, the blocks are not secured to the base or to one another, it may be found desirable in certain instances to employ a plurality of pegs or dowels 37, as indicated in Fig. 20, for insertion into aligned recesses 36 which may be formed in one or more of the faces of some or all of the blocks as well as the base, as is indicated in Fig. 19. By connecting the blocks to the base and to one another in this manner, a more stable construction will result.

While I have disclosed certain specific embodiments of my invention same are to be considered as illustrative and not restrictive and that the definition of the limitations of the invention is defined in the appended claims.

What I claim is:

1. Toy car construction elements comprising a base member and a plurality of blocks for interchangeable arrangements on said base member for providing bodies of various forms, some of said blocks being of cubical form, others of said blocks being of elongated form and each having one end thereof inclined to its base, others of said blocks being of elongated form and each having one end thereof inclined to its base and merging into its top through a curvilinear portion, and others of said blocks being of elongated form and each having one end thereof of curvilinear form.

2. The structure defined in claim 1 wherein all of said blocks are of equal height and equal width and wherein the bases of the third-mentioned blocks are of the same dimensions as the tops of the second-mentioned blocks, and wherein the last-mentioned blocks are each of a length equal to the combined length of two of the first-mentioned blocks.

3. Toy car construction elements comprising a base member and a plurality of blocks for various arrangements on said base member for providing car bodies of different forms, some of said blocks being of cubical form for forming the central portion of bodies, others of said blocks being elongated and having inclined ends for forming the rear ends of bodies, others of said blocks being elongated and having arcuate ends for forming the front ends of bodies, and still others of said blocks each having intersecting plane faces and an arcuate face for forming fenders for bodies.

4. The structure defined in claim 3 wherein said blocks other than those last-mentioned are each

of a width slightly less than one-half the width of said base member and together with a pair of said last-mentioned blocks equal to the width of the base member.

5. In a toy car, a base member, a plurality of circular recesses in the bottom of said base member for receiving ball members adapted to movably support said base member, ball-retaining means comprising a member pivoted to said base member and having an aperture therein for receiving a portion of each of said ball members for permitting rotation of said ball members within said recesses while retaining same within the recesses.
10. 6. Toy car construction elements comprising a base member and a plurality of blocks for interchangeable arrangements on said base member for providing various forms of toy automobiles of stream-line type; all of said blocks each having the opposite side walls thereof parallel, the top and bottom walls thereof parallel and at right angles to the side walls and one end wall perpendicular to the side, top and bottom walls, some of said blocks each having the opposite end wall thereof parallel to the first end wall; others of said blocks each having the opposite end wall thereof inclined to the bottom wall and merging into the top wall through a curvilinear wall portion; and others of said blocks each having the opposite end wall thereof of curvilinear form.

7. Toy car construction elements comprising a base member and a plurality of blocks for interchangeable arrangements on the base member for providing toy car bodies of various forms, some of said blocks being of cubical form, others of said blocks each having one end thereof inclined to its base, others of said blocks each having one end thereof inclined to its base and merging into its top through a curvilinear portion, others of said blocks each having one end thereof of curvilinear form, the bases of the second and last named blocks being equal and double that of one of the first named blocks, and the bases of the third named blocks being equal to the tops of the second named blocks.

15. 8. In toy car construction elements, a pair of base members having cooperating arcuate ends, and yieldable means detachably engaged with the base members for maintaining said ends in contact while permitting co-planular angular movement of the base members.

20. 9. In toy car construction elements, a pair of base members having cooperating arcuate ends, a slot in each base member extending transversely thereof, and a yieldable coupling removably disposed in said slots for maintaining said arcuate ends in rolling engagement with each other.

JULLIEN F. WINNEMORE. 30
